UNITED STATES PATENT OFFICE

2,424,584

DERMATOME ATTACHMENT

John D. Reese, Philadelphia, Pa.

Application November 20, 1945, Serial No. 629,875

19 Claims. (Cl. 128—305.5)

1

This invention relates to surgical instruments, more particularly to dermatomes, and has for an object to improve existing devices of this character.

Most dermatomes in use today are of the so-called "drum" type, such as disclosed in U. S. Patent No. 2,288,709 to G. J. Hood. These "drum" type dermatomes consist of a pair of spaced, parallel, approximately semi-cylindrical side walls joined along their semi-cylindrical edges by a curved bottom wall having a convex skin-engaging surface. A shaft is supported by the side walls for rotary and reciprocatory motion relative thereto about an axis coinciding with the axis of generation of the convex surface. A pair of posts are supported at one end from opposite terminal portions of the shaft, and carry at their other ends a graft-cutting knife adapted for cutting movement parallel to, and at a predetermined distance from, the convex surface.

It is customary to coat the convex surface with a suitable adhesive, so that, as the drum is pressed against donor area and rocked thereon, the skin adheres to the convex surface and is lifted thereby. At the same time, cutting action of the knife separates the skin from the donor area, leaving the graft adhering to the convex surface. The graft is thereafter removed from the drum and sutured or clamped to the injured area to be grafted.

In applicant's copending application Serial No. 618,523, filed September 25, 1945, there is disclosed an improved dermatome of the "drum" type, wherein the drum is provided with means for securing an adhesive-coated flexible strip to the drum with the intermediate portion of the strip overlying the drum convex surface, together with means for drawing the strip taut against said convex surface.

This flexible "graft-transfer" strip takes the place of the adhesive coating applied to the convex surface, the cutting operation leaving the graft adhering to the graft-transfer strip, the graft thereafter being applied to the injured area without removal from the graft-transfer strip, the latter providing excellent means for securing the graft in position and eliminating the necessity of using sutures or clamps.

There are several thousand of the drum-type dermatomes in use in the United States, none of which are provided with mechanism for securing thereto, and tightening thereon, the flexible graft-transfer strips, which strips are fully disclosed in applicant's copending application, Serial No. 583,983, filed March 21, 1945.

2

The cost of replacing these dermatomes with instruments equipped with the mechanism for holding and tightening the graft-transfer strips thereon might well be in the vicinity of \$1,000,000. A major portion of this expense could be avoided by the provision of an attachment for these dermatomes, which attachment could be purchased by a dermatome owner and easily attached thereto, such attachment including mechanism for holding a graft-transfer strip on the dermatome and drawing it taut against the convex surface thereof during use.

Therefore, another object of the present invention is to provide an attachment for dermatomes which will retain a flexible graft-transfer on the dermatome and draw the strip taut.

It is highly desirable that any such attachment be simple in construction, easily assembled on a dermatome, and capable of attachment to the dermatome without alteration of the existing structure, such as the drilling of holes, tapping of threaded openings, etc.

Therefore, another object of the invention is to provide an attachment for dermatomes which may be applied to such dermatome without any alteration of the latter.

Yet another object of the invention is to provide an attachment for dermatomes which may be assembled and/or applied to a dermatome without the exercise of unusual mechanical skill.

These and other objects are effected by the invention as will be apparent from the following description and claims taken in accordance with the accompanying drawings, forming a part of this application, in which:

Fig. 1 is a front elevational view of a dermatome on which is assembled an attachment embodying the principles of the present invention;

Fig. 2 is a side elevational view of the structure shown in Fig. 1;

Fig. 3 is a sectional view, taken along the line III—III of Fig. 2, looking in the direction indicated by the arrows;

Fig. 4 is a sectional view, taken along the line IV—IV of Fig. 2, looking in the direction indicated by the arrows;

Fig. 5 is a sectional view, taken along the line V—V of Fig. 2, looking in the direction indicated by the arrows;

Fig. 6 is a fragmentary side view of a modified arrangement for securing the attachment of Figs. 1 to 5 to the dermatome;

Fig. 7 is a sectional view, taken along the line VII—VII of Fig. 6, looking in the direction indicated by the arrows;

Fig. 8 is a plan view of one of the shims used to vary the spacing of the knife from the dermatome convex surface;

Fig. 9 is a perspective view of an attachment of modified construction;

Fig. 10 is a longitudinal sectional view of a dermatome with the attachment of Fig. 9 in use therewith;

Fig. 11 is a longitudinal sectional view of a dermatome with which is assembled a further modification of attachment;

Fig. 12 is a plan view of the structure shown in Fig. 11, portions thereof being broken away for the sake of clearness;

Fig. 13 is a fragmentary side elevational view of the left-hand end of the structure shown in Fig. 12;

Fig. 14 is an elevational view of the inner end of the bushing shown in Fig. 13;

Fig. 15 is an enlarged transverse sectional view of the clamp for the ends of the graft-transfer strip, as shown in Fig. 11; and

Fig. 16 is a side elevational view of a key suitable for operating the tightening mechanism of Figs. 11, 12 and 13.

Referring now to the drawings more in detail, particularly to Figs. 1 and 2 thereof, there is shown a dermatome which, of itself, forms no part of the present invention, being fully disclosed in applicant's copending application Serial No. 623,900, filed October 23, 1945, to which reference may be had for a detailed description thereof. It is believed sufficient to state here that the dermatome 10 comprises a spaced pair of parallel, semi-circular side walls 11 and 12, connected at their semi-circular edges by a curved bottom wall 13 having an outer convex surface 14, normally adapted to be coated with adhesive, for the purpose previously mentioned. The side walls 11 and 12 are connected at their upper edges by a handle 15 bridging the space therebetween and serving as a bearing for a shaft 16 slidably and rotatably journaled therein.

A pair of parallel posts 17 and 18 are secured on the terminal portions of the shaft 16 and carry at their outer free ends a pair of heads 19, to which is secured a blade-supporting structure, indicated in its entirety by the reference character 21. This blade-supporting structure may be drawn towards, and held against, the heads 19 by the finger nuts 22 and their associated structure, with the blade 23 held with its cutting edge in parallel predetermined spaced relation with respect to the convex surface 14, variations in the predetermined spacing of the blade 23 relative to the convex surface 14 may be obtained by insertion of shims 24, of the desired thickness, between the blade-supporting structure 21 and the heads 19 (Figs. 2 and 8). The structure so far described is disclosed in detail in applicant's copending application Serial No. 623,900, filed October 23, 1945.

The attachment for the dermatome just described, and constituting the subject-matter of the present invention, provides means for securing a flexible graft-transfer strip to the dermatome, and comprises a pair of side plates 31 and 32 of the same general shape as the dermatome side walls 11 and 12, but slightly smaller, and have notches 33 in their upper edges to receive the shaft 16 when the side plates are positioned against the outer surfaces of the side walls 11 and 12. The side plates are provided with circular bosses 34, 35 and 36 on their inner surfaces for close reception in mating circular open-

ings A, B and C, respectively, which are provided in the dermatome side walls 11 and 12 for use in supporting the dermatome or for other reasons not pertinent to the present invention.

It will be apparent that the mating of the bosses in the openings A, B and C will prevent movement of the side plates 31 and 32 in the planes of the latter.

A clamping block 37 extends between the bosses 10 33-33 and has terminal portions 38 mounted in the bosses, these terminal portions 38 being of non-circular cross-section to prevent turning of the clamping block. A clamping bar 39 likewise extends between the bosses 33-33 in parallel relation to the clamping block 37, the bar 39 being pivotally mounted on a rod or bolt 41 extending through the bosses and the side plates 31-32. A nut 42 retains the bolt 41 in position and the bolt thus serves to prevent separation of the side plates from the dermatome (Fig. 5).

The clamping block 37 and clamping bar 39 have roughened opposed surfaces adapted to clamp between them one end of a flexible graft-transfer strip (not shown), when the clamping bar is moved to clamping position by means of a handle 43, as described in the previously-mentioned copending application Serial No. 618,523, in which the same clamping mechanism is illustrated as built into the dermatome.

Referring now to Fig. 4, a shaft 51 is rotatably mounted in the opposed bosses 34-34 in the openings B-B. One terminal portion 52 of the shaft 51 extends through the boss 34 and its side plate 31 and is internally bored, as at 53, for reception of any suitable tool or wrench (not shown) which may engage the pin 54 traversing the bore 53, for rotating the shaft 51. A slot 55 extends longitudinally of the intermediate portion of the shaft 51, for reception of the other end of the graft-transfer strip whose one end is held by the clamping mechanism previously described. Thus, the two ends of the graft-transfer strip will be gripped with the intermediate portion of the strip engaging the outer convex surface 14 of the dermatome.

The projecting terminal portion 52 of the shaft 51 has its outer periphery toothed as at 56, for engagement by a pawl 57 pivotally mounted on the side plate 31 by the pin 58, and urged into engagement with the teeth 56 by a spring 59. When the shaft 51 is rotated clockwise, as viewed in Fig. 2, to hold and tighten the graft transfer strip, the teeth 56 will slip past the pawl 57, but counterclockwise rotation will be prevented by engagement of the pawl with the teeth, until such times as it is desired to release the strip, when the pawl may be disengaged from the teeth by movement of the pawl handle 60 to the left, as viewed in Fig. 2.

Inasmuch as it is frequently desirable to further tighten the graft-transfer strip by an amount less than that corresponding to the spacing of the teeth 56, a cam shaft 65 is mounted in the bosses 35-35 in such a position that the graft-transfer strip rests thereagainst in passing from the left end of the dermatome, as viewed in Fig. 2, to the slotted shaft 51, just described. The cam shaft 65 has a terminal portion 66 extending through the boss 35 and its side plate 31, this terminal portion being hollow, as at 67, and traversed by a pin 68 for engagement by the same tool or wrench used with the shaft 51. Similarly, the periphery of the terminal portion 66 is toothed, as at 69, for engagement by the pawl 70, pivotally mounted, at 71, on the side plate

31, and biased into operative engagement with the teeth 69 by the spring 72.

With the series of teeth 69 in the position shown in Fig. 2, the cam shaft 65 will be exerting minimum pressure on the contacting graft-transfer strip. Turning of the cam shaft 65 through 180° will put maximum pressure on the strip to tighten the latter, both ends thereof being already held by the previously-described mechanisms.

The bolt 41 and nut 42 hold the side plates 31-32 against the dermatome side wall at one end, and they may be held at the other end by screw 75 threaded into one end of the cam shaft 65, and nut 76 threaded on the terminal portion 66 of shaft 65.

In Figs. 6 and 7 there is illustrated a modified construction of attachment differing from that just described in that the side plates 80 are held against the dermatome side walls by hook portions 81. In this construction, the bosses may be omitted as well as the screw 75 and nut 76.

In Figs. 9 and 10, there is illustrated a modified construction of dermatome attachment for securing a graft-transfer strip to a conventional drum-type dermatome. The dermatome shown in Fig. 10, and indicated in its entirety by the reference character 100, differs in detail from that shown in Figs. 1 and 2, but involves the same basic construction, including a pair of opposed, parallel, semi-cylindrical side walls 101, joined along their semi-cylindrical edges by a curved bottom wall 102 having an outer convex surface 103. A cylindrical handle 104 connects the side walls 101 midway of the length of their upper edges, and provides a bearing for a shaft 105 mounted therein for rotation and reciprocation therein. A pair of posts 106 are mounted on the shaft terminal portions and have at their outer free ends heads 107 against which a blade-supporting bar 108 clamps a knife blade 109. Spacing of the blade-cutting edge 111 with respect to the convex surface 103 is varied by the insertion, between the blade and the heads 107, of shims 112 of the desired thickness, these shims being similar to the shims 24, illustrated in Fig. 8. The blade-supporting bar 108 is moved toward and away from the heads 107 by knurled adjustment nuts 113 of the tops of the posts 106, through interconnecting mechanism (not shown). For a detailed disclosure of this dermatome 100, reference may be had to applicant's Patent No. 2,366,054.

The attachment of Figs. 9 and 10 is, in effect, a separable liner 120 for the dermatome 100, and comprises a pair of semi-circular side walls 121 joined along their semi-cylindrical edges by a curved wall 122. The side walls 121 are provided with semi-cylindrical notches 123 at the centers of their upper edges to fit around the dermatome handle 104 when the liner 120 is inserted within the dermatome.

Securing mechanism 125 is mounted within the liner, at the right-hand end thereof as viewed in Figs. 9 and 10, and comprises a clamping bar 126 having an upper gripping edge 127 and a lower bearing edge 128. Tightening of the clamping bar by the pair of screws 129, threaded in bosses 130 on the inner surface of the liner's curved wall 122 forces the gripping edge 127 into holding engagement with the terminal portion 132 of the flexible graft-transfer strip 133, whose intermediate portion is positioned against the outer convex surface 103 of the dermatome.

The other terminal portion 135 of the graft-transfer strip is held by a securing mechanism

136, similar to the securing mechanism 125, and comprising the clamping bar 137 having a gripping edge 138 and a bearing edge 139, together with a pair of screws 140 for forcing the clamping bar into securing position with the gripping edge 138 holding the graft-transfer strip terminal portion 135.

The screws 140 are threaded into a supporting bar 141, pivoted at its lower edge, by pin 142, to the left-hand end of the liner 120. An adjusting screw 143 is threaded through the supporting bar 141, with its point engaging the curved wall 122 of the lever. The head of the screw 143 is provided with a suitable fingerpiece 144 by which it may be turned to move the supporting bar about its pivot 142. It will be apparent that as the supporting bar 141 is moved clockwise, as viewed in Fig. 10, the graft-transfer strip 133 will be tightened and the intermediate portion thereof drawn taut against the convex outer surface 103 of the dermatome.

In Figs. 11 to 16, inclusive, there is shown an attachment for use with a dermatome similar to that of Fig. 10, the parts thereof bearing the same numerals. In this modification, a bushing 150 is rotatably mounted in one of the circular side wall openings C and has secured thereto, by pin 151, a shaft 152 whose other end is rotatably mounted in bushing 153, which is prevented from turning by ribs 154 (Fig. 14) which slightly cut into and grip the wall of the opening C in which it is mounted.

The shaft 152 is of non-circular cross-section between the bushings 150 and 153, and has mounted thereon a pair of parallel arms 155, at whose free ends is mounted a bar 156. Inasmuch as the openings in the arms 155 are of a size and shape to closely receive the non-circular portion of the shaft, any rotation of the shaft will be imparted to the arms.

That end of the shaft which is journaled in the bushing 153 is slotted, as at 157, for insertion of the blade 158 of a suitable tool or key 159, or for the flat blade of a conventional screw-driver (not shown), by which the shaft may be rotated. A toothed ratchet wheel 161 is non-rotatably mounted on the shaft 152 adjacent the outer face of the bushing 153, and the teeth 162 thereof are adapted to be engaged and held from counter-clockwise rotation by the pawl 163, pivotally mounted on the bushing 153.

With this attachment, a long graft-transfer strip 165 is positioned as shown in Fig. 11, with the terminal portions 166 and 167 thereof held together by suitable clamping means, such as the C-clamp 168 (Fig. 15). The intermediate portion 169 of the graft-transfer strip engages the outer convex surface 103 of the dermatome, and the opposite portion 171 thereof is positioned beneath the rod 156. As the shaft 152 is rotated clockwise, as viewed in Fig. 11, the arms 155 will move the rod 156 downward against the portion 171 of the graft-transfer strip, thereby drawing the intermediate portion 169 thereof taut against the convex outer surface of the dermatome.

While the invention has been shown in several forms, it will be obvious to those skilled in the art that it is not so limited but is susceptible of various other changes and modifications without departing from the spirit thereof.

What is claimed is:

1. An attachment for use with a dermatome of the type comprising a hollow body member having an outer convex surface against which a flexible graft-transfer strip is to be temporarily retained taut; said attachment comprising a sup-

porting structure, first means carried by said supporting structure for securing to the latter one end of a flexible graft-transfer strip, second means carried by said supporting structure for securing to the latter the other end of said flexible graft-transfer strip with the intermediate portion of said strip positioned against the dermatome outer convex surface, said second means being adjustable relative to said supporting structure to draw said graft-transfer member taut against said dermatome convex surface.

2. An attachment as specified in claim 1, wherein in said supporting structure includes a pair of parallel spaced-apart side plates having axially-aligned openings therein constituting bearings, and said second securing means extends between said side plates and has terminal portions journaled in said bearing openings.

3. For use with a dermatome of the type comprising a hollow body member having a convex outer surface, an attachment for temporarily retaining a flexible graft-transfer strip taut against said dermatome convex outer surface; said attachment comprising a supporting structure adapted to be attached to the hollow body member of a dermatome of the type specified, first means carried by said supporting structure and adapted to grip one end of a flexible graft-transfer strip, and second means likewise carried by said supporting structure for securing the other end of said flexible strip with the intermediate portion of said strip against said convex outer surface and for pulling said strip to draw said intermediate portion of said strip taut against said convex outer surface.

4. Structure as specified in claim 3, wherein said second means pulls said strip in predetermined increments, and including cam means carried by said supporting structure for tightening said strip a portion of one of said increments.

5. For use with a dermatome of the type comprising a body member having a pair of spaced-apart side walls having pairs of axially-aligned openings therein and joined by a bottom wall having an outer convex surface, an attachment for temporarily retaining a flexible graft-transfer strip taut against said outer convex surface; said attachment comprising first means for holding one end of the graft-transfer strip and adapted to be supported in one of said pairs of axially-aligned openings, and second means for holding the other end of said strip with the intermediate portion of the latter against the convex outer surface and for pulling said strip to draw said intermediate portion thereof taut, said second means being adapted to be supported in another of said pairs of axially-aligned openings.

6. Structure as specified in claim 5, including cam means for further tightening said strip and adapted to be supported in yet another of said pairs of axially-aligned openings.

7. For use with a dermatome of the type comprising a body member having a pair of spaced-apart side walls having pairs of axially-aligned openings therein and joined by a bottom wall having an outer convex surface, an attachment for temporarily retaining a flexible graft-transfer strip taut against said outer convex surface; said attachment comprising first means for holding one end of said graft-transfer strip and adapted to be supported in one of said pairs of axially-aligned openings, and second means for holding the other end of said graft-transfer strip with the intermediate portion of said strip against said outer convex surface, said second means compris-

ing a shaft adapted to be rotatably supported in another of said pairs of axially-aligned openings, means for securing said other end of the graft-transfer strip thereto, and means for applying 5 rotary motion to said shaft to draw said strip taut against said outer convex surface.

8. Structure as specified in claim 7, including means for retaining said shaft in rotated position with said graft-transfer strip drawn taut 10 thereby.

9. An attachment for use with a dermatome of the type comprising a hollow body member having an outer convex surface against which a flexible graft-transfer strip is adapted to be 15 temporarily retained taut; said attachment comprising a body portion adapted to be positioned within the hollow body member of the dermatome, first means for securing one end of a graft-transfer strip to said body portion, second means for securing the other end of said graft-transfer strip to said body portion with the intermediate portion of said strip overlying the dermatome outer convex surface, and means for drawing said strip taut.

10. An attachment for use with a dermatome of the type comprising a hollow body member having an outer convex surface against which a flexible graft-transfer strip is to be temporarily retained taut; said attachment comprising a body portion adapted to be positioned within the dermatome hollow body, first means carried by said body portion for securing to the latter one end of a flexible graft-transfer strip, second means carried by the body portion for securing the other end of said graft-transfer strip thereto 20 with the intermediate portion of said strip positioned against the dermatome outer convex surface, and means for drawing said strip taut.

11. An attachment for use with a dermatome of the type comprising a hollow body member having an outer convex surface against which a flexible graft-transfer strip is to be temporarily retained taut; said attachment comprising a body portion adapted for reception within the dermatome hollow body, first securing means carried by said body portion for securing to the latter one end of a flexible graft-transfer strip, a supporting member pivotally mounted on said body portion, second securing means carried by said supporting member for securing to the latter the other end of said graft-transfer strip with the intermediate portion of said strip positioned against the dermatome convex surface, and means for adjusting said supporting member about its pivotal axis to draw said flexible graft-transfer strip taut.

12. For use with a dermatome of the type comprising a hollow body member having an outer convex surface, an attachment for temporarily retaining a flexible graft-transfer strip taut against said dermatome outer convex surface; said attachment comprising means for joining the two ends of a flexible graft-transfer strip, and means adapted to be positioned within said dermatome hollow body for taking up the slack in said strip after the ends thereof have been joined by said first-mentioned means, whereby the intermediate portion of said strip may be retained taut against the outer convex surface of the dermatome hollow body.

13. For use with a dermatome of the type comprising a hollow body having an outer convex surface, an attachment for temporarily retaining a flexible graft-transfer strip taut against said outer convex surface; said attachment compris-

ing a member adapted to connect the two ends of a flexible graft-transfer member within said dermatome hollow body, and means adapted to be positioned within said hollow body for adjustably tensioning said flexible strip after connection of the ends thereof by said member, whereby the intermediate portion of said strip may be drawn taut against the outer convex surface of the dermatome hollow body.

14. For use with a dermatome of the type comprising a hollow body having a convex outer surface, an attachment for temporarily retaining a flexible graft-transfer strip taut against said convex outer surface; said attachment comprising a pair of spaced securing members adapted to grip opposite ends of the flexible graft-transfer strip within the hollow body of the dermatome, with the intermediate portion of said strip against the dermatome convex surface, and means for moving one of said securing means towards the other of said securing means, to draw the graft-transfer strip taut.

15. For use with a dermatome of the type comprising a hollow body having a convex outer surface, an attachment for temporarily retaining a flexible graft-transfer strip taut against said convex outer surface; said attachment including a frame adapted to be positioned within the hollow body of the dermatome, a first securing means for securing one end of the graft-transfer strip to the corresponding end of the frame, a supporting member mounted on the frame adjacent the other end thereof for movement relative thereto, a second securing means for securing the other end of the strip to said supporting member, and means for moving said supporting member relative to the frame to draw the graft-transfer strip taut against the dermatome convex outer surface.

16. An attachment for use with a dermatome of the type comprising a body member having an outer convex surface against which a flexible

graft-transfer strip is to be temporarily retained taut; said attachment comprising a pair of holding means adapted to hold opposite ends of a flexible graft-transfer strip with the intermediate portion of said strip against the dermatome outer convex surface, and means supporting said pair of holding means relative to said dermatome body member, one holding means of said pair of holding means being adjustable relative to said

5 supporting means and to said dermatome body member for drawing said graft-transfer strip taut against said dermatome convex surface.

10 17. Structure as specified in claim 16, wherein said supporting means comprises a pair of plates having portions projecting therefrom for interfitting with mating portions of the dermatome body member.

15 18. An attachment as specified in claim 16, wherein said supporting means comprises a pair of plates adapted to abut the sides of the dermatome body member, said plates having bosses projecting therefrom and adapted to be closely received in mating openings in the sides of the dermatome body member.

20 19. An attachment as specified in claim 16, wherein said supporting means comprises a pair of plates adapted to abut the sides of the dermatome body member, said plates having hook-like portions adapted to engage edges of the dermatome body member sides to position said plates with respect to said sides.

JOHN D. REESE.
